UNITED STATES PATENT OFFICE.

CLYDE C. WILLIAMS, OF GUYMON, OKLAHOMA.

NUT-LOCK.

1,285,865.

Specification of Letters Patent.

Patented Nov. 26, 1918.

Application filed February 12, 1918. Serial No. 216,756.

To all whom it may concern:

Be it known that I, CLYDE C. WILLIAMS, a citizen of the United States, residing at Guymon, in the county of Texas and State 5 of Oklahoma, have invented certain new and useful Improvements in Nut-Locks, of which the following is a specification.

This invention relates to improvements in nut locks.

10 The main object of the invention is to provide a nut lock having an improved construction and arrangement of locking mechanism adapted to securely fasten the nut in its adjusted positions on the bolt and 15 which may be readily released to permit the nut to be removed.

Another object is to provide a nut lock which will be simple, strong, durable and inexpensive in construction, efficient and reliable in operation and well adapted to the 20 purpose for which it is designed.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 25 30 within the scope of what is claimed without departing from the spirit of the invention.

In the accompanying drawings:—

Figure 1 represents a perspective view of a nut shown applied equipped with this improved lock,

Fig. 2 is a detail transverse vertical section through the locking mechanism of the nut,

Fig. 3 is a side elevation of the portion of 40 the nut in connection with which the lock is used,

Fig. 4 is a perspective view of the locking set screw and its coöperating catch, and

Fig. 5 is a similar view of the catch detached.

In the embodiment illustrated, a bolt B of usual construction is shown on which is adapted to be mounted a nut 1 having one corner beveled as shown at 2. A bore 3 extends obliquely through this beveled corner portion and communicates with a bore 4 which receives the bolt B as is shown clearly in Fig. 2. The bore 3 is threaded to receive a set screw 10 and its outer end registers 50 with a seat 5 designed to receive the head 11 of the set screw. Radiating from the seat

5 are a plurality of grooves or notches 6 adapted to receive a catch 12 carried by the set screw 10, when the set screw is in locking position as shown in Fig. 2. The screw 60 10 has the usual kerf 13 in its head for the reception of a screw driver and extending at right angles from said kerf is a groove 14 in which is pivotally mounted the locking catch 12. This catch 12 is in the form of 65 a bar which is pivoted intermediately of its ends in groove 13, one end extending across the kerf 13 and the other end projecting beyond the periphery of the head of the screw as is shown clearly in Fig. 4. This catch 12 70 is provided at its inner end with a spring tongue 14' which is designed to rest on the bottom of the kerf 13 and operates normally to hold the outer end of the catch in locking engagement with one of the notches 6 75 formed in the nut face 2. This spring tongue 14' is yieldable under pressure exerted by the insertion of a screw driver in the kerf 13 as is shown in dotted lines in Fig. 2 and causes said catch to be tilted on said 80 insertion into the dotted line position shown in Fig. 2 thereby releasing the catch from the notch 6 with which it is engaged to permit the screw 10 to be moved.

In the use of this improved nut lock, the 85 screw 12 may be partially inserted in the bore 3 and the nut 1 screwed on to the bolt B until it reaches the desired position. The screw 10 is then moved inwardly by means of a screw driver inserted in the kerf 13, 90 the insertion of which operates to hold the catch 12 with its outer end swung outwardly so that the screw may be screwed home into operative position without said catch interfering with its turning. After the screw 95 has been moved inwardly to bring its point into biting engagement with the bolt B as shown in Fig. 2, the removal of the screw driver will permit the catch 12 to swing downwardly into locking engagement with 100 one of the notches 6 as shown in full lines in Fig. 2. It will thus be seen that the screw cannot be turned until after this catch is released and consequently the nut will be held securely locked on the bolt B. 105

To permit the removal of the nut, the insertion of the screw driver will operate to disengage the catch and permit the screw 10 to be moved outwardly a sufficient distance to disengage its point from the bolt and thus 110 permit the nut to be unscrewed in the usual manner.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

I claim:—

- 15 1. The combination with a nut having a bolt receiving bore and another bore communicating therewith and extending at an angle thereto, a set screw operable in said second bore, and coöperating elements carried by said nut and screw for locking the latter in operative position, said elements being releasable by the engagement of a screw driver with the screw.
- 20 2. The combination with a nut having a bolt receiving bore and another bore communicating therewith and extending at an oblique angle thereto, a seat surrounding the outer end of said second bore and provided with a plurality of radially extending notches communicating therewith, a set screw for insertion in said second bore having a head provided with a kerf adapted to be positioned in said seat, when the screw is in operative position, a latch pivotally

mounted on said screw head intermediately of its ends with one end intersecting said kerf and its other end projecting beyond the perimeter of said head and adapted to engage one of the notches radiating from the seat in the nut when the screw is in operative position.

3. The combination with a nut having a bolt receiving bore and another bore communicating therewith and extending at an oblique angle thereto, a seat surrounding the outer end of said second bore and provided with a plurality of radially extending notches communicating therewith, a set screw for insertion in said second bore having a head provided with a kerf adapted to be positioned in said seat, when the screw is in operative position, a latch pivotally mounted on said screw head intermediately of its ends with one end intersecting said kerf and its other end projecting beyond the perimeter of said head and adapted to engage one of the notches radiating from the seat in the nut when the screw is in operative position, 40 said catch being provided at its inner end with a spring tongue positioned to yieldably hold the catch in locking position.

In testimony whereof I affix my signature in presence of two witnesses.

CLYDE C. WILLIAMS.
